UNITED STATES PATENT OFFICE.

CARL SCHROTTZ, OF COLOGNE, GERMANY.

REBOUND-PREVENTING DEVICE FOR GAS-ENGINES.

SPECIFICATION forming part of Letters Patent No. 735,912, dated August 11, 1903.

Application filed February 7, 1901. Serial No. 46,341. (No model.)

To all whom it may concern:

Be it known that I, CARL SCHROTTZ, a subject of the German Emperor, residing at 31 Tempelstrasse, Cologne, Germany, have invented 5 certain new and useful Improvements in Rebound-Preventing Devices for Gas-Engines; and I do hereby declare the following to be a full, clear, and exact description of the invention, such as will enable others skilled in the 10 art to which it appertains to make and use the same.

My invention relates to an improved apparatus that is to be inserted into the pipe admitting gas to a gas-engine and whereby the 15 pressure in the neighboring pipes is rendered more nearly equable and the flickering of flames fed by the same is prevented.

The apparatus consists of a return-valve 20 preferably arranged within a chamber connected with the admission-pipe.

Of the accompanying drawings, Figure 1 is 25 a longitudinal section, and Fig. 2 a cross-section on line *x y* in Fig. 1, of the preferred construction of the herein-described apparatus.

The same letters of reference indicate the same parts in both figures.

In the drawings, *M* is a gas-pipe supposed 30 to be connected with the gas-main, and *F* is a feed-pipe supposed to be connected with the gas-engine and admitting gas to the same. Between both pipes is placed the air-tight chamber *C*, preferably made in the shape of a cylinder. Within this cylindrical chamber 35 and closely fitting one end of the same is placed the circular flange *B*, with a stud *S* in its center. The stud *S*, I prefer to cut off obliquely, as shown in the drawings. I further provide a flat lid or cover *V*, suitably hinged 40 at one end, which partly by its own weight and partly by the action of the spring *N* is normally pressed against the edge of the stud *S*.

In order to secure tight closing of the lid 45 *V* on the edge of the stud *S* and to prevent noise when the lid is rapidly closed, I prefer to provide a soft packing *P*, made of leather or any other suitable substance, on the lower side of the said lid.

The pressure of the spring *N* can be adjusted by means of the screw *O*, which passes through the wall of the chamber *C*, and therefore remains accessible at all times.

The operation of the herein-described apparatus is as follows: When the engine begins to suck, a certain reduction of pressure 55 in the chamber *C* will precede the lifting of the cover *V*. The spring *N* ought to be adjusted in such a way that the difference of pressure on both sides of the lid *V* is merely 60 sufficient to lift it very slightly, and thus a wider opening of the valve is only effected when the inertia of the stream of gas has accumulated. When the period of suction has attained its end and the cut-off valve of the 65 engine has closed, the flow of the gas will still continue for a short time until the increasing pressure in the chamber *C* gradually stops it. At this period, however, the lid *V*, being subjected to the pressure of the spring 70 *N*, besides the gas-pressure in chamber *C*, will close before the pressure in *C* has increased to the full amount of the pressure in *M* and will thereby prevent a rebound of the gas, which otherwise usually is effected by the 75 congestion of the gas in admission-pipes to gas-engines. It will readily be seen that the action of my apparatus is regulated not only by the pressure of the spring *N*, but also by the capacity of the chamber *C*, and since the 80 gas inclosed in the feed-pipe *F* will add its cushion action to that of the gas in the chamber *C* the size of the latter can be varied according to the length of the feed-pipe, and where the feed-pipe is sufficiently long the 85 chamber *C* might be omitted altogether without altering the nature of my invention. Likewise if instead of having a sufficiently long feed-pipe an elastic reservoir were provided in the feed-pipe—such as, for instance, 90 the rubber bag usually employed for the purpose—the same result would be obtained.

Having now particularly described and ascertained the nature of my said invention and in what manner the same is to be performed, 95 I declare that what I claim is—

An apparatus for preventing the rebound of gas in the feed-pipe of gas-engines, con-

sisting of a chamber arranged in the feed-pipe, said feed-pipe, where it discharges into the chamber, being formed in the shape of an obliquely-truncated stud having its discharge substantially in line with the flow of the gas through said feed-pipe, a hinged lid closing the oblique mouth of said stud, and a spring bearing upon said lid, in combina-

tion with exteriorly-operable means for regulating the pressure of the spring upon the lid. 10

In testimony whereof I have affixed my signature in presence of two witnesses.

CARL SCHRÖTZ.
